UNITED STATES PATENT OFFICE.

JAMES FRANK MATTHEWS, OF FALL RIVER, AND EDGAR F. HATHAWAY, OF BOSTON, MASSACHUSETTS, ASSIGNEES, BY MESNE ASSIGNMENTS, TO BARBER-COLMAN COMPANY, OF ROCKFORD, ILLINOIS, A CORPORATION OF ILLINOIS.

MACHINE FOR REREEDING WARP THREADS.

Application filed April 1, 1915, Serial No. 18,596. Renewed September 12, 1921. Serial No. 500,266.

To all whom it may concern:

Be it known that we, JAMES FRANK MATTHEWS and EDGAR F. HATHAWAY, citizens of the United States, and residents of Fall River, Massachusetts, and Boston, Massachusetts, respectively, have invented certain new and useful Improvements in Machines for Rereeding Warp Threads, of which the following is a specification.

10 Our invention provides means whereby the work of re-reeding a warp may be accurately, quickly and cheaply done, and, so far as we are aware, provides automatic mechanism for that purpose that is broadly 15 novel. The principal part of the work of drawing-in is that of putting the individual threads through the eyes of the several harnesses that may be employed, and, in some instances, also through the apertures of the 20 stop-motion drop-bars that may be employed.

“Re-reeding,” as it is called in the mills, provides a method whereby in case of damage to the reed or other cause making re- 25 reeding necessary, the main portion of the work already done, in drawing-in the warp, is preserved. Generally, although not always, each dent of the reed (the “dent” being the space between the parallel metal 30 members which are called “splits”) carries a plurality of threads; and in re-reeding, if the organization of the warp in the old reed can be preserved, the plurality of threads in each dent of the old reed may be 35 transferred by a single operation to a corresponding dent of the new reed, and thus a relatively large number of threads may be quickly handled.

Broadly, our invention provides means 40 whereby this may be automatically done, the threads being transferred accurately from the old reed to the new reed, and preferably in such manner that the entire group of threads in any given dent of the old reed 45 is transferred, through a single operation, to a corresponding dent of the new reed. Preferably, and as herein illustrated, the ends of the warp threads leading through the old reed are removed entirely and transferred to the new reed; but it will be obvious that a bight of the threads in the old reed may be drawn through the corresponding dents of the new reed. That is to say, so long as the threads in the old reed, or a

portion of each thread, is drawn through the 55 corresponding dent of the new reed, the warp is then made available in the new reed for further operation. Preferably, we also provide, as herein illustrated, a form of mechanism in which means are provided positively 60 and constantly engaging the old reed and traversing lengthwise of the same and across the dents by engagement with the splits, said means also having the additional function of engaging the thread or group of 65 threads in each dent of the old reed and presenting said thread, or group of threads, at a single operation into the corresponding dent of the new reed.

One of the detail objects of our invention 70 is to provide a form of machine for this described purpose which is portable and designed for being properly positioned upon the loom so that the work of re-reeding may be performed upon the loom without 75 removing the warp and the rest of the weaving equipment from the loom; but, of course, the re-reeding operation may be performed apart from the loom. Power for driving the mechanism may be transmitted to the 80 actuating shaft by any suitable or convenient mechanism.

In the accompanying drawings we have illustrated a convenient form of mechanism embodying the principles of this invention, 85 in which:

Figure 1 is a side elevation partly in section showing the relative dispositions of the two reeds and the transfer member.

Figure 2 is a detail view in vertical section showing the means for mounting the movable transfer member.

Figure 3 is a plan view of the same apparatus.

Figure 4 is a front elevation thereof.

Figures 5 and 6 are detail view of the transferring member and of its forward support respectively.

Figures 7, 8 and 9 are diagrammatic views in side elevation illustrating the action of 100 the yarn transferring member.

The mechanism for automatically re-reeding the warp threads is intended to be set directly upon the loom, and to that end is mounted on the base or frame *c* whose forward end rests upon the breast beam *w'*, and whose rear end rests upon the transverse beam of the lay *x*, as shown in Figure 7.

When the device is thus placed on the loom, the warp threads y still remain in the harness and in the reed a . The free ends of the warp yarns are loosely clamped together by any suitable form of clamp a^2 faced with textile fabric or other suitable material and yieldingly pressed together by compressing springs a^4 . The clamp is put on before the warp ends are severed from the cloth already woven so as to preserve the proper order and arrangement of the warp threads. The reed a is carried over an elevated horizontal rod a^3 and laid upon parallel smooth horizontal supporting bars or tracks a' which are themselves supported by upright standards c' on the base c . The clamp a^2 hangs in socket c^* in said standards. As the threads are gradually withdrawn from the clamp, the latter settles to the bottom of the sockets c^* .

The yarn-transferring member comprising the hook or needle g suitably supported and actuated, as will be hereinafter explained, is mounted on a standard e^3 carried by the transversely movable carriage e so that the transfer member may start at one end of the reed and be shifted step by step to engage and re-reed each successive warp thread across the width of the loom. The ends of the warp threads y being held in vertical position by means of the cross bar a^3 and the clamp a^2 , the carriage is shifted to one side in position to bring the hook needle g into alignment with the warp threads at the extreme right of the reed a . The second reed b which is to receive the warp threads is suspended from a shiftable carrier rod b^3 freely supported upon rollers c^3 (Fig. 4) carried by the standards c^2 mounted on the carriage e by means of depending arms b' provided with locking or retaining springs b^2 . The reed b is suspended between the rear end of the needle supporting bearing g^4 and the vertical portions of the warp threads y .

The principle of action is that the hook needle g is passed through the appropriate dent of the reed b which is to receive the first or extreme right-hand warp thread and moves back into position to engage said warp thread and draw it forward through said reed dent, as indicated in the diagrammatic Figures 8 and 9. This operation is repeated with each successive dent and warp thread until all the threads have been drawn out of the clamp a^2 and the reed a and drawn through the reed b .

To efficiently and reliably perform this operation we employ means for supporting the two reeds in proximity and with their splits lying in substantially parallel vertical planes, and a coordinated reciprocating transfer member or needle alined with a device for opening successively the dents of the receiving reed for the passage of the

transfer member into position to engage the appropriate warp thread or group of warp threads contained in the corresponding dent of the warp-containing reed, the delivery of the warp threads to the transfer member being accomplished by a device which acts in co-operation with the reed itself to engage the appropriate thread or group of threads in their containing dent, and position them to engage the barb of the transfer member or needle. The mechanism also embraces a means for feeding the carriage e which carries the transfer member progressively step by step across the loom along the reeds, and to secure perfect alinement each reed is supported so as to be freely movable in the direction of its length or across the loom to accommodate itself to the successive position of the respective reed openers. Provision is also made for removing each warp thread from the hook after it has been drawn through the second reed, which action is effected by means of a movable stripper member working transversely to the path of the hook needle. The reeds are mounted on their respective supports so as to be easily capable of longitudinal shifting or movements for compensating purposes as will be hereinafter explained.

We will now explain in detail the mechanical devices or movements illustrated in the drawings for carrying out the objects of the invention. The old or warp-containing reed a is mounted loosely on the tracks a' so as to permit the longitudinal compensating or shifting movement requisite to maintain the successive dents of the reed in proper alinement with the successive positions of the transfer needle g , it being understood that the reed itself forms an element in co-operation with the yarn-delivering element to position the successive warp threads or group of threads where there is more than one thread to the dent, to the transfer needle. In the specific form of the invention shown, the device for maintaining the reed in proper relationship or position is also employed for engaging and presenting the warp threads properly to the transfer needle itself. This comprises a forwardly rotating cam d secured to a shaft d' mounted in a swinging supporting bracket d^{10} , driven by a horizontal transmission shaft d^2 (Fig. 3), by mitre gear connections d^3, d^4 . This cam d is slotted in a substantially radial direction with the two adjacent edges slightly offset in an axial direction so that the cam forms approximately a single turn of a helix, whereby upon each complete revolution it passes out of the dent with which it is engaged into the next adjacent dent of the reed. This construction not only allows the cam to work its way into each successive dent of the reed to maintain proper alinement of that dent with the transfer needle,

but also enables the cam to engage the thread or threads contained in the successive dent and shift them to the opposite face of the cam in position to be engaged by the barb or hook of the needle. By referring to Figures 8 and 9 it will be seen that the segregated warp element that is seized by the transfer member g is the one resting in the dent of the reed a next beyond the dent in which the cam d is resting so that the split of the reed a immediately beyond the cam is interposed between the warp element that is being seized by the needle and the cam itself. The aforesaid split of the reed acts to hold the warp thread to be seized slightly away from the face of the cam so as to be properly engaged by the hook or barb of the needle which is turned toward the cam. It will therefore be seen that the cam acts through each successive split of the reed to present the adjacent segregated warp element to the needle. The shaft d^2 is driven by a mitre gear connection from the horizontal transverse shaft d^6 which is concentric with the axis of the swinging bracket or arm d^{10} and is itself driven from the vertical shaft d^6 by another mitre gear connection. In order to prevent the weight of the cam from resting upon the reed, we provide an adjustable stop screw d^{11} tapped into the bracket d^{10} in position to engage a stop shoulder d^{12} formed on the bearing bracket of the shaft d^6 which is carried by the standard e' on the carriage e . This arrangement permits the vertical adjustment of the opener cam d in relation to the reed a and also permits the cam to be swung up entirely free from the reed into inoperative position indicated in dotted lines in Figure 1 where it is detachably held by means of the retaining arm or detent k which is pivotally mounted upon the carrier rod b^8 .

The opener cam for operating on the receiving reed acts on a similar principle so far as concerns the positioning of the new reed, but owing to the vertical position of the reed b , there is no need of mounting it on a swinging bracket. This opener comprises an off-set slotted cam f similar to cam d but rotated in the opposite direction to the cam d by its supporting horizontal shaft f' which is rotated by a mitre gear connection with vertical drive shaft f^2 , the bearings for which are carried in the vertical standard or bracket e^2 branching from the standard e' .

The transferring hook or member g is secured in a cylindrical socket or holding member g^6 which is mounted to slide backward and forward in the horizontal bearing sleeve g^4 carried by the bracket e^2 mounted on the carriage e . The bearing sleeve g^4 is provided with a partly spiral cam slot g^3 through which projects a pin or stud g^2 secured to the socket member or holder g^6 so that as the needle approaches its advanced

position when adjacent to the cam d , the transferring member whose hook up to that time has been in the vertical position, is given a quarter turn toward the adjacent warp thread in order to engage the same. 70

The warp yarn, by the complete rotation of the cam d , which is also a yarn-positioning member, has been transferred from the left-hand side of the cam d to the right-hand side, in close proximity to which the needle hook travels. By the action described, the hook and the warp threads are brought into proper operative relationship to allow the warp thread to be engaged by the hook. 75 Moreover, the cam, by separating the thread or group of threads contained in a given dent and shifting it to the other side of itself, prevents the hook from seizing a thread of the next succeeding dent. 80

The hook now travels back, drawing with it the yarn end through the second reed b . After the hook has passed back to the front side of the reed b , a swinging stripper member o , provided with a thin hook-like blade at its forward end, is swung across the 90 thread between the hook and the reed in order to disengage the yarn end from the hook so as to leave the hook free to advance into position to engage the next warp thread. 95

The opener or cam f is arranged in the same vertical plane as the needle g and acts as a spreader to open the appropriate dent in the reed b to allow the needle to pass through. The mounting of the reed on the 100 transversely shiftable carrier rod b^3 allows the reed to accommodate itself perfectly to the position of the opener and of the needle in case there is any slight variation between the spacing or intervals of the dents and the 105 step by step movements of the carriage transversely of the loom.

Power is applied to the actuating mechanism by means of the handle h^8 mounted eccentrically on the wheel h^4 secured to the 110 horizontal shaft i^2 . The pin of the handle h^8 passes through a slot in the lever h^3 , which lever is connected with the upwardly extending slotted arm or lever h by means of the hub h^2 . In the slot in the upper arm h is a pin h' secured to a sleeve g^{12} (Fig. 2) which is rotatable upon the needle holder g^6 but is held against longitudinal movement with relation to the needle holder. The pin h' extends through a guide slot g^{13} formed in 120 the bearing sleeve g^4 .

From the shaft i^2 are actuated all the other trains of mechanism for advancing the carriage intermittently, actuating the devices d and f , and stripping the yarn from the hook. 125

To advance the carriage, there is secured to the base or platform e a transverse rack bar e^5 which forms one of the guides for the carriage e and also has engagement with the pinion r carried by the vertical shaft r^2 130

mounted in the bearing sleeve or bushing r^3 which is clamped in the bed of the carriage by nut r^4 . The ratchet arm r^5 carrying at its front end a spring pressed pawl r^6 and slotted at its rear end to rest astride the shaft i^2 , is provided with a pair of anti-friction rollers i^7 which engage opposite sides of the rotating cam i^8 which is fixed to the shaft i^2 so as to impart a reciprocatory movement to said ratchet arm r^5 . The front end of the arm r^5 is supported and guided by an oscillatory arm or lever r^9 mounted at the top of the shaft r^2 above the ratchet wheel r^{10} . To provide for the pawl engaging a greater or less number of ratchet teeth at each stroke, we employ an adjustable hood or pawl stripper r^{11} which is mounted on the sleeve bushing r^3 so as to be adjustable circumferentially into position adjacent to the pawl so as to keep the pawl from engaging any more of the ratchet teeth than is desired. This permits the step by step travel of the carriage to be varied according to the coarseness or fineness of the reeds.

25. The stripper o is slidingly mounted in a swivelled sleeve o' and has at its left-hand end a sleeve n^3 engaging an eccentric pin n^4 on the wheel n^2 which is compounded with the spur gear n' meshing with the gear n .

30. The gear n is driven by means of a mitre gear connection i^5 from the main drive shaft i^2 .

The actuating or driving mechanism for the openers or cams d and f is arranged as follows: On the shaft i^2 is secured a disk i^8 carrying a projecting pin i^4 in position to enter and engage on successive revolutions one of a series of six radial grooves m' formed in the adjacent face of the over-lapping star wheel m so as to produce one-sixth of rotation of said wheel for each revolution of the drive shaft i^2 , the wheel m remaining stationary during the period that it is out of engagement with said actuating pin i^4 . The star wheel m is thus held stationary by reason of engagement of the locking segment i^6 with one of the recesses m^7 of the star wheel, said locking segment being fixed to and concentric with the disk i^8 .

40. On the shaft of the wheel m is secured a spur gear m^2 meshing with the pinion m^3 which transmits intermittent rotation to the shaft m^4 through mitre gear connections. On the rear end of the shaft m^4 is secured a mitre gear m^5 intermeshing with mitre gear m^6 which is secured to the vertical shaft f^2 . By means of spur gears f^3 , d^{13} , the same intermittent rotation is transmitted to shaft d^6 operating the opener d that shaft f^2 has in operating opener f .

The cams and other working parts are so co-ordinated that the carriage e is shifted through the ratchet r^{10} when the needle g is retracted toward the front end of its socket and is entirely withdrawn from the verti-

cally hung reed b . At this stage the arm h acting upon the needle holder g^6 serves to advance the needle just as the cam f is rotated into position to open the dent of the reed b in line with the advancing needle. The cam f , being radially slotted with the adjacent edges of the slot off-set, acts to disengage the cam from one wire while engaging it with the next one, the cam being of sufficient thickness to open or widen the interstitial space or dent to allow the needle to easily enter and pass through into position alongside the cam d whose movement is co-ordinated to shift one thread or group of threads from the left to the right-hand side adjacent to the hook of the needle, as already described. The needle g is then retracted, and as it is retracted the hook is turned to vertical position still holding the thread so as to pass easily through the reed b . After being retracted clear of the reed, the stripper member or hook o swings across the thread and pulls it out of the hook of the needle. By reason of their engagement with the respective wave-cams d and f , the reeds a and b will be accurately positioned for each successive traverse of the needle.

The supplemental guide or support g^8 (Fig. 6) may be located close to the reed just in advance of the shaft f' which carries the opener cam f in order to form a support for the needle in its advanced or operative position. This guide member consists of a plate g^8 having a key hole slot g^9 to allow the passage of the needle and hook when the hook is vertical and the slot is left open at the bottom to enable the warp thread to be removed from the guide plate after the needle has been retracted until the hook has passed entirely clear of the guide plate.

The cams d and f each serve a two-fold purpose. They both serve to correctly correlate the reed dents with the needle at each successive operation and to maintain them in proper correlation while the needle does its work by reason of the fact that said cams have an intermediate rotation as previously described. The cam d also serves through the medium of the reed which it positions as an agent in presenting the yarn to the needle. The cam f acts also as an expander or opener for spreading apart the splits of each successive dent to facilitate a passage of the transfer member.

In some classes of work it may be desirable for the attendant to advance the carriage more rapidly than the regular pace of the machine set by the automatic mechanism. To enable this to be done, we have provided the pinion shaft r^2 with a hand wheel t adapted to be grasped by the operator and turned to any extent desired. This is advantageous also for setting the carriage quickly to the proper position to begin its normal automatic operation.

- We claim as our invention:
1. The combination of means for supporting a warp-containing and spacing reed whose individual splits act to separate the 5 individual warp elements from one another, means to support a warp-receiving reed in co-operative relationship with the first-named reed, a warp-selecting device acting in co-operation with the splits of the first-named reed to position the individual warp elements successively for transfer, and a transferring device acting to engage the warp elements successively and draw them from the first reed into the appropriate 10 dents of the second reed.
  2. A selective mechanism for a warp-transferring machine embracing, in combination, means to support a warp-containing and spacing reed, means mounted to engage 15 the successive splits of the reed and co-operating therewith to position the successive warp threads, and a drawing-in device whose action is correlated with said reed and to which the threads are presented by 20 the thread-positioning means.
  3. A re-reeding machine for transferring drawn-in warp threads from one reed to another, comprising, in combination, means for supporting a new reed; drawing-in mechanism to operate on the new reed embodying a drawing-in member and a reed-opening device alined therewith; traversing feed mechanism to give a relative traversing movement lengthwise of the said reed and 25 between said reed and the drawing-in mechanism; means for supporting the old reed with its splits lying in planes substantially parallel with the splits of the new reed; and a thread-engaging device arranged to engage 30 successively the threads contained in the successive dents of the old reed; the said thread-engaging device and drawing-in mechanism being co-operatively arranged in relation to the old reed.
  4. A re-reeding machine for transferring drawn-in warp threads from one reed to another, comprising, in combination, a support for a new or receiving reed, a support for an old or warp-containing reed, a warp-transferring member arranged to pass 35 through the successive dents of the receiving reed and to engage and retract through said dents the thread or threads contained in the corresponding dents of the warp-containing reed, and means engaging the warp-containing reed to correctly position the threads contained in the successive dents for engagement with said transfer member.
  5. The combination of a support for a 40 warp-containing reed, a support for a warp-receiving reed, means for automatically alining said reeds with each other, a warp-transferring device, and means for automatically operating said warp-transferring device to draw warp threads from successive dents of the warp-containing reed into the corresponding dents of the warp-receiving reed.
  6. The combination of means for supporting a warp-containing reed and a warp-receiving reed for movement transversely of the loom, a transversely movable carriage arranged to travel intermittently along the reeds, reed-engaging and positioning members operatively mounted upon said carriage, and a warp-transferring device also carried by said carriage and actuated to draw the successive warp threads from the first-named reed through the second reed.
  7. The combination of a support for a 45 yarn-containing reed and a support for a yarn-receiving reed, a reciprocating hooked needle, means for opening the dents of the warp-receiving reed in line with said needle, and means co-operating with the warp-containing reed for selecting and bringing into engagement with said needle the successive warp threads carried in the warp-containing reed.
  8. The combination of means for slidably supporting warp-containing and warp-receiving reeds, a warp-transferring member mounted to pass between the successive dents of the warp-receiving reed to engage the successive warp threads contained in the corresponding dents of the other reed and draw them through the warp-receiving reed, means for shifting the warp-transferring member step by step along said reeds to operate upon successive warp threads, and compensating 50 means for preserving proper alinement between the two reeds and the warp-transferring member.
  9. In a re-reeding machine, the combination of a support for a warp reed containing properly drawn-in warp threads, means to hold a second warp reed in position to receive the warp threads from the first reed, a carriage adapted to traverse said reeds longitudinally, devices mounted 55 on said carriage for alining the corresponding dents of said reeds, and a hook member also mounted on said carriage in co-operative relationship to said alining devices to engage the threads contained in the different dents of the first reed, and draw them through the corresponding dents of the second reed.
  10. The combination of a stationary support on which a warp-containing reed may 60 be mounted, means for holding the warp threads taut, a transferring needle, and a rotary split cam mounted in position to pass between successive dents of the reed on successive revolutions and to engage and shift an individual warp thread at each revolution adjacent to the path of the needle, the latter being movable into position adjacent 65

- to said rotary cam to engage individual warp threads and withdraw them from said reed.
11. In a re-reeding machine, the combination with a support on which a warp-containing reed may be slidably mounted, of a co-operating cam member mounted to traverse said reed longitudinally, while maintaining continuous engagement with the successive dents thereof, said cam member being constructed and arranged to contact with the successive splits of said reed to engage and present the yarn in position to be engaged by a warp-transferring member.
12. The combination of a support for a warp-containing reed, a carriage shiftable along said reed, a rotary reed-engaging and yarn-engaging cam mounted upon said carriage and movable into and out of engagement with the successive dents of said reed, and adjusting means by which the position of said reed-engaging member in relation to said reed may be varied.
13. The combination of means for slidably supporting a reed, a movable yarn-transferring member shiftable step by step along said reed, and a rotary reed-engaging slotted off-set cam shiftable in unison with said yarn-transferring member to open the dents of said reed and acting to preserve proper alinement between the transferring member and the successive dents of said reed.
14. The combination with supports for two reeds arranged in juxtaposition, a carriage arranged to be shifted intermittently along said reeds, a reciprocating yarn-transferring device mounted on said carriage, and rotary engaging and positioning members arranged to pass between and spread the dents of the respective reeds also mounted on said carriage, one of said rotary members acting to lay successive warp threads in engagement with the transferring device, and the other rotary member acting to open successive dents of the reed for the entrance of the transferring device.
15. The combination of a support for a longitudinally movable reed containing a set of warp elements separated from one another by the individual splits of the reed, means to support a warp-receiving reed in juxtaposition to the other reed, means for correlating the position of the two reeds whereby their corresponding dents may be properly alined for the warp-transferring operation, a warp-transferring member acting to successively engage the individual warp elements held between each pair of splits of the first mentioned reed, and means for retracting said transferring member from the dent of the first reed through the corresponding dent of the second reed.
16. The combination with a support for a warp-containing and spacing reed whose splits separate and position the individual warp elements, a reciprocatory hooked needle, and a selective device co-acting with the successive splits of the reed to pick up in succession the individual warp elements and lay them into engagement with the hooked needle, a support for a second reed properly positioned in relation to said first reed, and means for retracting the hooked needle in engagement with each successive warp element through the successive dents of the second reed.
17. In a re-reeding machine, the combination of a support for a warp-containing reed whose splits form means for separating the individual warp elements from one another and act to position the warp elements for the transferring operation, a support for a warp-receiving reed, a warp-transferring device for engaging the entire warp element between each pair of splits of the first-mentioned reed and transferring it into the corresponding dent of the second reed, and means for intermittently shifting said transferring device lengthwise of said reeds, said shifting means being adjustable to vary the extent of such shifting movement.
18. A selective device for warp-transferring embracing in its construction a support for a warp-containing spacing reed, and a co-operating feed member arranged to engage the successive warp elements in conjunction with the successive splits of said reed to position the warp elements in orderly sequence for engagement with a drawing-in device.
19. A re-reeding machine for transferring warp threads from the dents of an old reed to the corresponding dents of a new reed comprising, in combination, means to support an old reed containing the drawn-in warp elements and a new reed for receiving said warp elements with the respective reed splits lying in substantially parallel planes, said supporting means permitting the free independent length-wise movement of each reed, a carriage arranged intermittently to travel length-wise of the reeds, re-reeding and warp-handling mechanism on said carriage comprising a reed opener for engaging and opening successively the dents of the new reed and a warp-engaging device co-operating with the splits of the old reed to position the warp elements successively for transfer, and a transfer device movable through the dent of the new reed into position to engage and withdraw the warp element contained in the corresponding dent of the old reed, and means for retracting said transferring device to remove said warp element from the old reed into the new reed.
20. In a re-reeding machine, the combina-

tion of means for supporting two reeds in juxtaposition to each other to permit a longitudinal movement of each reed, a warp-transferring member, reed-positioning members for correlating the respective reeds, the transferring member and the successive warp elements, and actuating mechanism by which the reed-positioning members and the warp-transferring member are operated to transfer successive warp threads from one reed to the other.

21. In a re-reeding machine, the combination of supports for a warp-containing reed and a warp-receiving reed, a warp-transferring member for drawing successive warp elements from the first reed into the second, and means for correlating the corresponding reed dents, the warp-transferring member and the warp to cause the warp-transferring member to engage each successively segregated warp element and draw it into the appropriate dent of the receiving reed.

22. In a re-reeding machine, the combination of means for supporting a warp-containing and a warp-receiving reed in juxtaposition to each other, a reed-positioning mechanism and a warp-transferring mechanism, means for supporting said reed-positioning and warp-transferring mechanism in operative relation to the reeds, and means for securing a progressive relative movement between the reeds and the reed-positioning and warp-transferring mechanism whereby successively segregated warp elements may be transferred from one reed to the other.

23. In a re-reeding machine, the combination of means for receiving and supporting a warp-containing and a warp-receiving reed in juxtaposition to each other while permitting them to have longitudinal movement, a carriage, reed-engaging and positioning means, a warp-transferring means mounted on said carriage, and an actuating mechanism for intermittently shifting said carriage and intermittently operating said warp positioning means.

24. A re-reeding machine having, in combination, supports for two reeds, thread-drawing mechanism, means for causing relative feed movement between the drawing mechanism and the reeds, and means for automatically adjusting the position of the reeds

with reference to the drawing mechanism.

25. The combination of a support for a 55 reed containing a sheet of warp threads, a reed opener engaging the splits of the reed and the sheet of threads, and a needle reciprocable alongside the reed opener for taking threads engaged by said opener. 60

26. A re-reeding machine having, in combination, a support for a warp-containing reed, a support for a new reed, a device to open successive dents of the new reed, and a needle reciprocable through the opened 65 dents of the new reed and to and away from a position alongside the warp-containing reed, to take the contents of each dent of said warp-containing reed and draw the same through the new reed. 70

27. A re-reeding machine having, in combination, means for supporting two loom reeds one of which contains a sheet of warp threads, and a needle reciprocable through the other reed and into operative relation to 75 the sheet of threads for drawing threads through said other reed.

28. A re-reeding machine having, in combination, means for supporting two loom reeds, and automatic mechanism for transferring threads from one reed to the other. 80

29. A portable re-reeding machine for use in the loom, having, in combination, a base adapted to rest upon the lay and the breast beam of the loom, supports on the base for the old and the new reed, and mechanism on the base for transferring threads from the old to the new reed. 85

30. A portable re-reeding machine for use in the loom, having, in combination, a support adapted to be mounted on the loom, and re-reeding mechanism mounted on the support and operating between the lay and the breast beam of the loom. 90

31. The combination of a support for a warp-containing reed, means to hold distended the warp contained in the reed, a rotary member in the nature of a screw engaging the splits of the reed and the sheet of warp threads, and a hook movable into 100 position alongside said member to take threads engaged by said member. 95

In testimony whereof we have hereunto set our hands.

J. FRANK MATTHEWS.
EDGAR F. HATHAWAY.
